UNITED STATES PATENT OFFICE.

KARL FRITJOF NYSTROM, OF MONTREAL, QUEBEC, CANADA.

CAR-ROOF.

1,297,488.

Specification of Letters Patent. Patented Mar. 18, 1919.

Application filed January 26, 1918. Serial No. 214,020.

To all whom it may concern:

Be it known that I, KARL FRITJOF NYSTROM, a subject of the King of Sweden, residing at Montreal, in the Province of Quebec and Dominion of Canada, have invented 5 certain new and useful Improvements in Car-Roofs, of which the following is a specification, reference being had therein to the accompanying drawings.

10 The invention relates to car roofs of that type in which the running board and saddles are formed of wood. The present invention comprises the peculiar construction of an auxiliary saddle upon the wooden saddle for 15 securing the running boards to the wooden saddle. Another feature of the invention is the means for draining from between the adjacent running boards and also certain arrangements and combinations of parts more 20 fully hereinafter set forth.

In the drawings:

Figure 1 is a cross-sectional view through a car roof embodying my invention;

Fig. 2 is a plan view of the running board 25 and saddle construction;

Fig. 3 is a cross-sectional view on the line 3-3 of Fig. 2;

Fig. 4 is a perspective view thereof.

In the construction of roofs of the type in 30 which the running board saddles are formed of wood, it is usual to secure the running boards directly to the saddle by nails or similar securing means; but this construction is open to several objections, such as the 35 splitting of the saddles by the nails, the working loose of the running boards, etc. With my improved construction, these objectionable features are avoided by reason 40 of securing the running boards to an auxiliary saddle mounted upon the wooden saddle, the arrangement of the mounting being such that the wooden saddle is reinforced thereby.

A represents the roofing sheets having the 45 upstanding side flanges B which are embraced by the carline caps C and also provided with the upstanding end flanges D which are embraced by ridge caps E. The junction caps F embrace the adjacent ends 50 of the adjacent carline caps and ridge caps to weather-proof the car roof. G represents the wooden saddles in the plane of the carline caps C and supported thereupon, and secured in place by the saddle bolt H.

55 For securing the running boards and at the same time to reinforce the wooden saddle

and to avoid splitting the latter, the following construction is employed: I represents the running boards extending longitudinally of the car roof and J the auxiliary 60 saddles formed of pressed sheet metal and located at intervals of the car roof upon the wooden saddles. These auxiliary saddles have the laterally extending portions J' projecting outwardly beyond the sides of 65 the wooden saddles G, a sufficient distance for the passage of the bolts K therethrough for securing the running boards thereupon. The auxiliary saddles J are secured to the wooden saddles G by the ears J² struck 70 downwardly from the laterally extending portions J' to embrace each wooden saddle and by the bolts M passing through the saddle and ears, this arrangement of auxiliary saddle with its ears embracing the wooden 75 saddle reinforcing the latter.

For draining the space between the adjacent running boards upon the auxiliary saddles, the latter are provided with channel shaped grooves L in the laterally extending 80 portions J', extending downwardly toward the outer edges thereof.

By the above construction the advantages of the wooden saddle are retained while its disadvantages are avoided. At the same 85 time the structure is adapted to perform its functions as well as does an all steel running board saddle, which latter is objectionable on an all steel car roof, since the contacting steel surfaces of the saddle and car 90 roof cause rapid wear and corrosion on both the saddle and the roof.

What I claim as my invention is:

1. In a car roof, the combination with a wooden saddle, of a sheet metal saddle thereupon, ears struck out from said sheet metal saddle and extending downwardly to embrace said wooden saddle, means for securing said ears to said wooden saddle, and a running board secured upon sheet metal 100 saddle.

2. In a car roof, the combination with a wooden saddle, of a sheet metal saddle thereupon, portions extending laterally therefrom, ears struck downwardly from said 105 metal saddle, secured to said wooden saddle, and running boards secured end to end upon said laterally-extending portions.

3. In a car roof, the combination with a saddle formed of sheet metal, of spaced running boards extending transversely thereof and secured thereto, said saddle having a 110

downwardly and outwardly inclined groove formed in the space between said boards.

4. In a car roof, the combination with a wooden saddle having its under surface conform to the contour of the roof and its upper surface horizontal, of an auxiliary saddle resting upon the upper surface of said wooden saddle and secured to the latter, and a running board secured to said auxiliary saddle.

5. In a car roof, the combination with a wooden saddle having its under surface conform to the contour of the roof and its upper surface horizontal, of an auxiliary saddle resting upon the upper surface of said wooden saddle and provided with downwardly-extending portions secured to said wooden saddle and with laterally-extending portions, and a running board secured upon said laterally extending portions.

6. In a car roof, the combination with a wooden saddle having its under surface conform to the contour of the roof and its upper

surface horizontal, of a saddle bolt extending through said wooden saddle and securing the same to the car roof, an auxiliary saddle resting upon the upper surface of said wooden saddle and secured to the latter independent of said saddle bolt and a running board secured to said auxiliary saddle.

7. In a car roof, the combination with a wooden saddle having its under surface conform to the contour of the roof and its upper surface horizontal, of an auxiliary saddle resting upon the upper surface of said wooden saddle and secured to the latter, said auxiliary saddle projecting outwardly beyond the sides of said wooden saddle, and running boards secured to the outwardly-projecting part of said auxiliary saddle, a portion of said outwardly-projecting part being downwardly and outwardly inclined to provide drainage.

Signed at the city of Montreal, Quebec, Canada, this 3rd day of January 1918.

KARL FRITJOF NYSTROM.
